UNITED STATES PATENT OFFICE.

BERNHARD FRANKE, OF NEW YORK, N. Y.

IMPROVEMENT IN REVOLVING ORDNANCE.

Specification forming part of Letters Patent No. 33,998, dated July 29, 1862.

To all whom it may concern:

Be it known that I, BERNHARD FRANKE, of the city, county, and State of New York, have invented new and useful Improvements in Breech-Loading Repeating-Cannons; and I do hereby declare that the following is a full and exact description of the same, reference being had to the accompanying drawings, which make part hereof, and in which—

Figure 1 represents a perspective view of the cannon with its appendages; Fig. 2, a longitudinal vertical section of the same through the middle thereof; Fig. 3, a view from above of the spring-catch which stops the revolution of the wheel holding and carrying the several breeches as the breeches come in succession opposite the rear of the barrel; Fig. 4, a face and edge view of the wedge-shaped wheel which operates the spring-catch, Fig. 3.

The same letters refer to the same parts on all the drawings.

The carriage of my improved cannon is well known and in common use, and therefore needs no particular description, as I do not claim any improvement in gun-carriages, and I do not intend to limit myself to any particular one. The barrel of the cannon, with the wheel containing the separate breeches firmly attached to it, rests upon trunnions on the carriage in the usual way, and the rear of the breech-wheel is supported by a screw, x , for elevating or depressing the aim.

The barrel of my cannon may have any of the well-known forms of cannon-barrels, except at the rear end. It has no breech, but is bored larger than its caliber for the reception and withdrawal of separate breeches. These breeches may be made of steel, and are bored of the caliber of the barrel, have their vent or nipple, and when in place the end toward the barrel enters and fits into the enlarged cavity of the rear of the barrel, as shown at A b, where, while being discharged, it is firmly held by the stop o .

The breeches are held in a solid horizontal wheel bored for their reception in radial positions. I prefer six of these breeches, but a different number may be used. This breech-wheel is also bored vertically at its center for the reception of a shaft, on which it revolves. (Marked

g .) Near its outer periphery, on its lower side, it has a face cog-wheel, the teeth of which are shown at u u , extending entirely around, just within its periphery, and into this cog-wheel work the cogs of a pinion (shown at v) upon the shaft n . This shaft and pinion are operated at pleasure by applying the hand to the radial arms d at the end of the pinion-shaft n . By moving these arms the pinion will revolve, and of course carry the breech-wheel around.

The breech-wheel is placed not only on the shaft g for support, but also within a circular rim, C , with a strong bottom plate, to which the shaft is firmly attached, and which extends in front of the rim, and by any well-known devices holds the barrel.

The breeches are so placed in the breech-wheel that when not protruded into the rear end of the barrel they are flush with the outer circumference of said wheel, and will revolve freely therewith when power is applied to the handles d . As the breeches are loaded they are revolved with the breech-wheel toward the rear of the barrel, and as each arrives there the spring-catch e drops into the notch in the breech-wheel, (shown in Fig. 3,) arresting the motion of the wheel. The breech in rear of the barrel is then in position to be moved forward into its place in the barrel in condition to be discharged. This motion is effected by the revolution of the shaft t , which is provided with a finger, y , taking into a notch, z , and with a sector-pinion, s . This notch z is cut away on its front in such a manner that when the breech is carried to its place in the barrel the finger will slip out and press it no farther, while the sector-pinion s will still continue to work in the sliding rack r and carry the stop o (sliding in a groove in the shaft g) up until it is in position to resist the recoil of the breech. Motion may be given to the shaft t by applying the hand to the handle a , or by any well-known means.

After the discharge, reversing the motion of the shaft t will withdraw the stop o and afterward retract the breech into the breech-wheel, after which the said wheel will again be prepared to revolve and bring the next loaded breech to the barrel. As the handles d are again moved to revolve the breech-wheel the wedge or inclined surface of the wheel F , (shown

at 12 in Figs. 1 and 4,) coming against the spring-catch *ee*, will draw it out of the notch, thus allowing the breech-wheel to revolve, and will keep it out until the wheel *F* and the spring-catch *ee* resume the position shown in Fig. 1.

The parts should be so adapted that the spring-catch will drop in the wheel and stop it the moment the breech gets into the proper position for being pushed forward into the barrel. This is effected, as shown in the drawings, by causing one revolution of the shaft *n* to rotate the breech-wheel the space between the centers of the adjacent breeches.

A circular plate, *I*, is fastened upon the top of the breech-wheel, by the nut *h* or otherwise, in such a manner as to cover closely all the nipples or vents, except the one belonging to the breech, which has been inserted into the barrel.

For the purpose of facilitating the swabbing and loading the breeches, I place two or more

spout-shaped projections, *ca*, from the rim *O* opposite the mouths of some of the breeches, when one of the breeches is inserted into or is opposite to the barrel.

Having clearly described my improvements and their mode of operation, what I claim as my invention, and desire to secure by Letters Patent, is—

1. The combination of the breech and the stop *b* with the finger *y* and the rack and pinion *r* *s*, operating substantially in the manner and for the purpose set forth.

2. The combination of the plate *I* with the breeches and nipples, in the manner and for the purpose described.

BERNHARD FRANKE.

In presence of—

W. P. N. FITZGERALD,
JAS. E. WEST.
